UNITED STATES PATENT OFFICE

MARTHA W. CAUGHLAN, OF OAKLAND, CALIFORNIA

REFLECTOR

Application filed March 7, 1928. Serial No. 259,697.

My invention has for its object a reflector adapted to collect the light emanating from a light source and reflect the same and by a single reflection to cause all of the reflected rays to pass out crossing on a focal line and within predetermined limits.

A further object is a reflector of the character described having upper and lower portions wherein the reflected rays from the upper part of the upper portion and from the lower part of the lower portion are directed downward with respect to the rays emanated from the lower part of the upper portion and from the upper part of the lower portion.

15 A further object is a reflector of the character described having an end closure with a relatively narrow light emanating aperture substantially coincident with the said focal line.

20 A further object is a reflector of the character described wherein a plane glass front is employed through which the reflected rays are transmitted and which glass is relatively narrow and long and wherein the said glass is inclined with respect to the horizontal axis of the reflector.

Other objects will appear from the drawing and specification which follow.

These objects I attain by forming my reflector surface in two portions joined together preferably at the common elliptical periphery, which I have called in my description below, the master ellipse.

25 The lower reflector surface (below the said master ellipse) is formed of successive and diminishing ellipses lying in planes at successively increasing angles with the plane of the master ellipse as the ellipses descend and diminish, and said ellipses have minor axes parallel with the minor axis of the master ellipse.

The upper portion of the reflector is also formed of ascending diminishing ellipses of increasing inclination to the plane of the 40 master ellipse, and all of said ellipses having their minor axes parallel with the minor axis of the master ellipse.

45 The vertex of the angle of inclination of the upper ellipses falls on the extended major axis of the master ellipse on one side and the

vertex of the angle of inclination of the lower ellipses falls on the prolonged major axis of the master ellipse and on the opposite side of the said master ellipse.

50 Although I prefer to form the upper and lower portions with a common master ellipse, they may each be formed with its own master ellipse and of different magnitude, without departing from the spirit of my invention.

In the drawing—

55 Fig. 1 is a side elevation of a lamp of my invention and its projected beam.

Fig. 2 is a vertical central longitudinal section through one form of the lamp of my invention.

60 Fig. 3 is a horizontal mid-section and Fig. 4 is a front view of the lamp of Fig. 2.

Fig. 5 is a diagrammatic illustration of the method of producing the lower reflector surface.

65 Fig. 6 is a diagram in plan of one half of the master ellipse of Fig. 5.

70 Figs. 7 and 8 are other elliptical sections of successive ellipsoids taken at right angles to the paper of Fig. 5 and through different portions of the lower reflecting surface.

75 Fig. 9 is a space diagram showing the conic relation of the several curves of the lower portion of the reflector of Figs. 2, 3, 4.

80 Figs. 10 and 11 are space diagrams of the several conics of the upper portion of the reflector of Figs. 2, 3, 4.

85 Fig. 12 is a space diagram combining in a single figure the principal conics of Figs. 9, 5 and 11 of the upper and lower portions of the reflector.

Fig. 13 is a perspective view of an illuminated surface in front of the lamp.

Throughout the figures similar numerals refer to identical parts.

90 The upper portion of one form of the lamp of my invention is shown generally by the numeral 1 and the lower portion by the numeral 2.

95 Assume that it is desired to distribute the entire illumination from the lower half lamp as a band of light whose upper limit shall be the horizontally projected ray 3 and whose lower limit shall be the downwardly projected ray 4 and whose lateral dispersion shall 100

be between the extreme limiting rays 34, 46. See Figs. 3 and 5.

First draw the line 4 through a point 7 such that the distance 7, 8 will give the desired dimension to the front portion of the completed lamp. Continue the line 4 until it intersects the line 3 at a point 9 (see Figs. 1 and 9).

With the point 9 as a center and the line 10 7—9 as a radius describe the circular arc 7, 10; choose now a point 11 which is to be the light source of my reflector. About the points 10, 11 as foci construct an ellipse 12 with major axis 14—13 which will give the desired size to the finished lamp and give the desired lateral light dispersion between the rays 46, 34 as shown in Figs. 3 and 10. Such an ellipse is indicated at 12 having vertices 13, 14.

On the circular arc 10—7 take any other 20 point as 15, draw a line through 15—11 and lay off thereon the line 16—17 equal in length to the major axis 13—14 and such that 11—17 equals 15—16. Construct on the line 16—17 as a major axis the ellipsoid whose trace is 25 the ellipse 18 and whose foci are 11, 15 respectively.

Pass a plane through the line 19 perpendicular to the plane of the paper and passing through the points 15 and 9 it will cut the ellipsoid 18 in an ellipse 58, which ellipse in 30 plan will be as shown in Fig. 7. Every point in such ellipse is common to its corresponding ellipsoid surface.

In the same way select any other point as 35 20 and with the same length of major axis as 13, 14 and with the foci 20—11 describe the ellipsoid whose trace is the ellipse 21 and cut this with a plane through line 22 perpendicular to the plane of the paper of Fig. 5 40 and passing through the focus 20 and the point 9, this plane 22 will then cut the ellipsoid 21 in the ellipse 51 of Figs. 5 and 8. In like manner conceive ellipsoids all having the same major axis equal to the line 13—14 and 45 all having the same common focal point 11, but whose remote foci lie upon the circular arc 10—7. Cut each of these ellipsoids with a plane passing through its remote focus, as 15—20 and through the point 9.

From each of these ellipsoids there will 50 then be cut an ellipse such as 58, and 51, the largest of these ellipses will be the master ellipse 12 and the smallest will be the point 7. The ellipses will decrease in magnitude 55 and increase in eccentricity as they descend from the remote focus 10 to the remote focus 7.

The lower surface of my reflector is made 60 up of an infinite number of such ellipses as 12, 58, 51 etc. every point in which is common to its corresponding ellipsoid, all of which have a common focus 11.

All of the reflected rays from the lower 65 portion of the reflector will now issue in the planes of these respective ellipses which pass

through the point 9 and will be confined between the horizontal plane of ray 3 and the downwardly directed plane through line 4 and in proof thereof note that a ray of light originating at one of the foci 11 of an ellipsoid will be reflected from every point within said ellipsoid and therefore every point on its elliptical section which has been chosen and will pass through the other ellipsoid focus which by construction is located on the arc 10, 15, 7 and my surface is constructed of an infinite number of such inclined diminishing elliptical sections.

Note that every point on every one of the ellipses as those shown in Figs. 6, 7 and 8 is 80 a point on an ellipsoid, one of whose foci is on the arc 10—7 and in the plane of the respective ellipse and in which plane the corresponding reflected rays will issue.

For example referring to Fig. 6, a light 85 ray originating at 11 will be reflected at 30 passing through the focus 10 and emerging as the ray 31. Likewise a ray reflected from 11 at the point 54 will issue as the ray 32 also passing through the focus 10 and a ray from 11 to the point 33 will issue as a ray 34 also passing through the focus 10, and all in the plane of the figure and of the ellipse 12.

The ellipse 58 of Fig. 7 which is cut from the ellipsoid whose tracer is 18 (see also Fig. 5) by the plane through the line 19 is entirely made up of points all taken from the said ellipsoid 18 whose proximate focus is 11 and whose remote focus is 15 and such points will therefore reflect from any point 40 a ray 100 originating from the light source 11 through the remote focus 15 and issue as the ray 41, and will all lie in the plane of the paper of Fig. 7 and therefore in the plane 19, 9 perpendicular to the plane of the paper of Fig. 5, likewise the ray originating at the proximate focus 11 will be reflected from the point 43 105 on the ellipse 51 of Fig. 8 through the remote focus 20 as indicated at 44.

The same is true of every other point down 110 to and including the point 7 into which the diminishing ellipses cut from their respective ellipsoids at last are merged.

The rear vertices of all of the inclined ellipses above described lie upon one branch 115 of an hyperbola.

Applying the law of the hyperbola, that the 120 difference between the distance of any point thereon from the remote and from the proximate foci, is equal to a constant, and referring particularly to Figs. 5 and 9, the two hyperbolic foci are 9 and 11 respectively. The point 13 will be one point upon the branch 45 of such a hyperbola, and 9, 13 minus 11, 13 which is plotted in Fig. 5 at the point 87, will 125 be the hyperbolic constant and is equal to 9, 87, that is the radius of the circular arc 79, struck from 9 as a center, and is concentric with the arc 10, 15, 7, and distant therefrom 130

the distance 87, 10 which equals 13, 14 the major axis of the family of ellipsoids.

Every point in the curve 45 is also a point on an ellipsoid having such a major axis and therefore the distance 77, 11 equals the distance 77, 78. The same is true of every other point on the curve 45 which is therefore a hyperbola.

The curve 14, 90, 91, 7 traced by the vertices 10 of the descending ellipses as 58, 51, each cut from its corresponding ellipsoid, is an arc of an ellipse 88, having the foci 9 and 11. The distance 9, 10 plus 10, 14, plus 14, 11 is the major axis of the ellipse 88, and the arc 10, 15, 20, 7 being struck from a center 9, every point thereon is at a constant distance equal to 9, 10 from 9.

To prove that curve 14, 90, 91, 7 is an arc of ellipse 88. If we take any point as 90 on said curve, and prove that 90, 11 plus 90, 9 equals 100, 14, a constant quantity such condition satisfies the law of the ellipse—see Figs. 5 and 9. Now, 90, 11 plus 90, 9 may be written as 90, 11 plus 90, 15 plus 9, 15; but 90, 11 plus 90, 15 equals 13, 14 because point 90 is in the ellipsoid 18; also 9, 15 equals 9, 10 because they are radii of a circle whose center is 9; hence 90, 11 plus 90, 15 plus 9, 15 equals 13, 14 plus 9, 10. Referring to Fig. 9; 100, 14 may be written as 100, 9 plus 9, 10 plus 10, 14 which is equal to 9, 10 plus 13, 14. Hence 90, 11 plus 90, 9 equals 100, 14, the major axis of ellipse 88 and point 90 is therefore on said ellipse. The same will hold true with any other point on the arc 14, 90, 91, 7 and hence said arc is a portion of the ellipse 88.

A preferable form for the upper portion of my reflector is one which shall collect all rays not heretofore reflected upon the lower described portion and after a single reflection of said rays will project them upon the same surface as the rays emanating from the lower reflector at a predetermined and substantial distance in front of the said reflector. In other words the reflected beam from the upper lamp portion will be superimposed upon the beam previously described and as indicated in Fig. 1.

To attain such a surface on the line 3, 50 choose the point 59 and for simplicity in calculations such that the distance 59—10 shall be equal to the distance 10—9 and construct a circular arc about 59 as the center and passing through the point 10. This is indicated 55 in Figs. 11 and 12 by the arc 61—10.

With the distance 13—14 (which is the major axis of the master ellipse of Fig. 5) and with 11 as a center describe an arc and choose thereon any point 61, draw any other line 60 through 59 and between 61 and 10, it will intersect said arc at some point 63. Where it intersects the arc at 63 draw the line 66, 63, 65 through 11.

With 11 as a proximate focus and 63 as a 65 remote focus construct an ellipsoid whose

trace will be 69 and whose major axis 66, 65 is equal to the line 13, 14 and a plane 59—63—67 normal to the paper will intersect said ellipsoid in an ellipse and every point in which as demonstrated above in connection with the lower portion of my reflector will reflect light originating at the proximate focus 11 such that it will pass through the point 63 and emerge on the aforesaid plane 59—67.

Another such ellipsoid whose trace is the ellipse 70 and whose major axis is 71, 72 will be cut by a plane normal to the paper through 59, 68. The points 67, 68 respectively will be vertices of two such elliptical sections and will lie upon the rear of the upper reflector surface.

The upper portion of my reflector is composed of an infinite number of such ellipses cut from their respective ellipsoids, all of which ellipsoids have a constant major axis, namely equal to the major axis 13—14 of the master ellipse 12 of Fig. 5, and all will have a common focus 11.

Every ray of light reflected from the upper portion of my reflector will therefore emerge in a plane normal to the plane of the paper.

The remote foci of the several ellipses will lie upon the circular arc 10—63—61 having 59 as a center.

The proximate vertices of each of the said ellipses will lie upon the curve 13, 67, 68, 61, and this curve will be a segment of an ellipse whose foci are 11 and 59.

As proof that this curve is an elliptical segment note that the distance from 11 to any point on any of the ellipses plus the distance from the said point to the circular arc 61, 63, 10 will be a constant because they satisfy the law of the ellipse and the distance from the said circular arc to the point 59 is a constant by construction.

The sum of these two constants is of course constant and this satisfies the definition of an ellipse.

The remote vertices of the inclined ellipses of the upper reflector portion will lie upon an hyperbola 61, 14. This will be evident from the fact that a similar group of ellipses in the lower reflector have their remote vertices upon an ellipse and their proximate vertices upon an hyperbola which are confocal at 9 and 11 whereas in the upper half, the proximate vertices lie upon an ellipse with their remote vertices upon an hyperbola 120 which are confocal at 11 and 59.

It will now be understood that every ray of light issuing from the light source 11 will be but once reflected and will pass through the line of foci 7, 10, 61 and that therefore an extremely narrow aperture about the said line is all that is necessary to admit of all of the rays passing out.

The thickness of the glass employed to cover the said aperture may be made relatively thin 130

and narrow as it is seldom necessary to illuminate a horizontal angle as wide as that indicated between the lines 34 and 46 of Fig. 6 but rather that in commercial practice outgoing rays between much narrower limits may be employed. The forward portion of the reflector may be removed and an obscure end portion 47-47 placed thereover, said end portion containing only a narrow vertical aperture as shown at 48, being substantially on 10 the focal line 61, 63, 10, 15, 20, 7.

The narrow glass front in the slot 48 will be substantially normal to the mean ray in the reflected beam, and will be directed downwardly; that is, the glass front will be inclined forward from the vertical (see Figs. 2 and 12) and therefore it will not reflect back rays from their own headlights to drivers along the road and in front of my light.

It will now be seen that every ray of light 20 from the source 11 and which impinges on any point of the reflecting surface will be reflected but once and emerge through the inclined aperture 48 and will be confined beyond the point 59 within the vertical limits 3 and 4 and 25 between the horizontal limits 34, 46 of Fig. 10.

For example referring to Fig. 3 there will be substantially 99% of the spherical candle power from 11 reflected and projected within the said limits.

It is also to be observed that fifty per cent of the total candle power from the light source 11 will be reflected from those surface portions to the left of a vertical plane 35 through 11 in Figs. 2 and 3 and that the beam of this 50% reflection will be comprised between the vertical limits 3 and 80 and the horizontal limits 82 and 83.

The illuminated surface in front of the lamp will therefore receive substantially 99% 40 of the original light from the source 11 and this will be concentrated in the proportion of 50% of said light within substantially 1/15 of said illuminated area (see 84 Fig. 10) and 45 49% over the remaining 14/15 of said area (see 85 of Fig. 10), the brighter portions being central, and all of said illumination being below the horizontal plane of the line 3.

The reflector above described and shown in 50 the figures as embodying one form of my invention is a preferred form but from the description it will be apparent that various other basic dimensions may be used as the distance between the foci, the distance of the 55 point 7 below the line 3, the position of the point 61 above the line 3, and by my method, reflecting surfaces may be constructed securing the desired result without departing from my invention and I desire to be understood as 60 claiming all such.

While I have shown and described my reflecting surface as constructed about a longitudinal plane and employed the term vertical plane these are to be considered only 65 as descriptive and relative to the drawing

and it is to be understood that the reflecting surface may be moved into any other position or angle or rotated as the case may be.

I claim:

1. A reflecting surface formed of a family of diminishing ellipses, said ellipses produced by the intersections of a family of ellipsoids with a pencil of planes, said ellipsoids having a common proximate focus and having remote foci on a vertical arc drawn from a center on the axis of and to the rear of said surface and said pencil of planes drawn through said center and said remote foci respectively. 70

2. A reflecting surface consisting of a family of diminishing ellipses whose remote foci lie in a vertical arc drawn from a center on the axis of and to the rear of said surface and whose rear vertices lie on an hyperbolic arc. 80

3. A reflecting surface as set forth in claim 1 wherein the said arc is normal to the said planes. 85

4. A reflecting surface as set forth in claim 2 wherein the said arc is normal to the said ellipses. 90

5. A reflecting surface formed of a family of diminishing ellipses, said ellipses produced by the intersections of a family of ellipsoids with a pencil of planes, said ellipsoids having a common proximate focus and having remote foci on an arc drawn from a center on the axis of and forward of said surface and said pencil of planes drawn through said center and said remote foci respectively. 95

6. A reflecting surface consisting of a family of diminishing ellipses whose remote foci lie on an arc drawn from a center on the axis of and forward of said surface and whose rear vertices lie on an elliptic arc. 100

7. A reflecting surface as set forth in claim 5 wherein the said arc is normal to the said planes. 105

8. A reflecting surface as set forth in claim 6 wherein the said arc is normal to the said ellipses. 110

9. A reflector comprising a reflecting surface portion formed of a family of diminishing ellipses, said ellipses produced by the intersections of a family of ellipsoids with a pencil of planes, said ellipsoids having a common proximate focus and having remote foci on a vertical arc drawn from a center on the axis of and to the rear of said surface and said pencil of planes drawn through said center and said remote foci respectively, and having another reflecting surface portion formed of a family of diminishing ellipses, said ellipses produced by the intersections of a second family of ellipsoids with a second pencil of planes, said ellipsoids having the said common proximate focus and having remote foci on a vertical arc drawn from a different center on the axis of and forward of said surface and said second pencil of 115

120

125

130

planes drawn through said different center and said remote foci respectively.

10. A reflector comprising a reflecting surface portion consisting of a family of diminishing ellipses whose remote foci lie in a vertical arc drawn from a center on the axis of and to the rear of said surface and whose rear vertices lie on an hyperbolic arc, and having another reflecting surface portion
10 consisting of a family of diminishing ellipses whose remote foci lie in a vertical arc drawn from another center on the axis of and forward of said surface and whose rear vertices lie on an elliptic arc.
- 15 11. A light projector comprising a light source, a reflecting surface positioned about said light source, every point on which surface is positioned such that its distance from said light source plus its distance from a
20 circular arc forward of said light source and struck from a center to the rear of said light source is a constant, said circular arc being vertical and lying in the median longitudinal plane of the reflecting surface.
